RAILWAY SWITCH CONTROLLING APPARATUS

Melvin A. Penrod, Murrysville, Pa., assignor to
The Union Switch & Signal Company, Swiss-
vale, Pa., a corporation of Pennsylvania

Application July 19, 1934, Serial No. 736,032

16 Claims. (Cl. 246—141)

My invention relates to railway switch controlling apparatus of the type wherein a railway switch is controlled by a manually operable lever and by a traffic controlled contact and wherein a release means is provided for controlling the switch when the traffic controlled contact is open.

One feature of my invention is the provision of release means for controlling each succeeding operation of a switch while the traffic contact is open, only if the switch has completed an operation in response to the last previously attempted control by the release means.

I will describe two forms of apparatus embodying my invention, and will then point out the novel features thereof in claims.

In the accompanying drawing, Fig. 1 is a diagrammatic view showing one form of apparatus embodying my invention. Fig. 2 is a diagrammatic view showing a modification of a portion of the apparatus illustrated in Fig. 1.

Similar reference characters refer to similar parts in each of the views.

Referring first to Fig. 1, the reference characters 1 and 1^a designate the track rails of a stretch 25 of main track Y which is divided by insulated joints 2 to form a track section a—d. The track section a—d is provided with a switch F leading into a side track Z. Track section a—d is also provided with a track circuit comprising a battery f connected across the rails adjacent one end 30 of the section, and a track relay designated by the reference character T and connected across the rails adjacent the opposite end of the section.

35 Switch F is operated by a mechanism M which may be of the fluid-pressure motor type. Mechanism M is controlled by a lock magnet m and by normal and reverse control magnets n and r for causing mechanism M to operate switch F to the normal or the reverse position respectively. Magnets n and r are controlled by a manually operable lever V, by a time releasing device E, and by a lock relay L. Magnet m is controlled by lever V and by a switch indication relay K.

45 As shown in the drawing, lever V has a normal position N, a normal detector lock position x, a normal indication lock position B, a reverse indication lock position D, a reverse detector lock position y, and a reverse position R. Lever V operates various contacts, each of which is closed during a given portion of the movement of lever V from one of its extreme positions N and R to the other. The portion of the movement of lever V during which each of the contacts 50 operated by lever V is closed, is indicated by a

reference character adjacent the symbol for the contact, such, for example, as reference character Nx adjacent the symbol for contact 30, which indicates that contact 30 is closed while lever V is in its N position or in its x position or in any other position between these two positions.

5 Lever V also operates a contact mechanism of the well-known quick switch type, designated by the reference character QS. Quick switch QS is operated by lever V in such a manner that its contact 5—6 becomes closed when lever V passes the x position in going from its position B to its position N, this contact remaining closed thereafter until the lever, in moving from its position D to its position R, passes the y position, whereupon contact 5—6 will open and contact 7—8 will close. Contact 7—8 will then remain closed until lever V next passes the position x, going from the position B to the position N.

20 Lever V is also provided with a latch contact 29 which is operated in a well-known manner by a latch mechanism associated with lever V. Contact 29 is open when lever V is in either of its extreme positions N and R, but becomes closed when the leverman operates the latch preparatory to moving lever V between its N and R 25 positions.

Movement of lever V between its x and its B positions is controlled in a usual and well-known manner by a normal lock magnet NM controlling 30 a dog 3 which engages a notched segment 4 rigidly attached to lever V. Movement of lever V between its y and D positions is similarly controlled by a reverse lock magnet RM.

35 Time releasing device E may be of the well-known manually actuatable screw type in which the period of operation is not measured but is variable to some extent by the leverman. Operation of such a release, however, enforces an appreciable time delay in the control of other parts 40 of the apparatus by the device E.

45 Releasing device E is equipped with two normally closed contacts 13 and 25 which open at the beginning of each operation of device E and which again close when device E is returned to its normal position. Device E also has a contact 21 which is closed only at a mid-point in the operation of device E between its normal and reverse positions. A fourth contact 12 of device E is closed only when device E is in its reverse position. The construction of device E is such that there is an enforced time delay between the opening of contacts 13 and 25 and the closing of contact 21, and also between the opening of contact 21 and the closing of contact 12 when 50 55

device E is operated from its normal to its reverse position. Similar time delays are enforced between the opening of contact 12 and the closing of contact 21, and between the opening of contact 21 and the closing of contacts 13 and 25 when device E is operated from its reverse to its normal position.

Lock relay L is normally energized by a circuit controlled by track relay T, but can also be energized by a circuit controlled by contact 21 of release E.

Switch indication relay K is of the polarized type, and is so controlled by a pole-changer P operated by switch F as to be energized by current of normal polarity when switch F is in its normal position and to be energized by current of reverse polarity when switch F is in its reverse position. Relay K is also controlled in part by contact 25 of release E.

As shown in the drawing, all parts are in their normal condition, that is, lever V and release E are in their normal positions, switch F is in its normal position, and section a—d is unoccupied. With section a—d unoccupied, relay T is energized. With relay T energized, relay L is energized by its circuit passing from terminal b of a suitable source of current not shown in the drawing, through contact 20 of relay T, wire 22, and the winding of relay L to terminal o of the same source of current. With release E in its normal position and with relay L energized, normal switch control magnet n is energized by a circuit passing from terminal b, through contact 13 of release E, contact 14 of relay L, wire 15, contact 16 of lever V, and the winding of magnet n to terminal o. A second circuit is also closed for the winding of magnet n, passing from terminal b, through contact 18 of lever V, and the winding of magnet n to terminal o. With switch F in its normal position and with release E in its normal position, relay K is energized by current of normal polarity in a circuit passing from terminal b, through contact 23 of pole-changer P, wire 24, contact 25 of release E, winding of relay K, wire 26, and contact 27 of pole-changer P to terminal o. On account of latch contact 29 being open, the circuit for lever lock magnet NM through contact 30 of lever V is open, and hence magnet NM is deenergized and dog 3 controlled by magnet NM is in engagement with the associated segment 4 of lever V, thereby preventing movement of lever V beyond its x position.

I will now assume that with all parts of the apparatus thus in their normal condition, the leverman desires to operate switch F to its reverse position. He will therefore close latch contact 29, causing lock magnet NM to be energized by its circuit passing from terminal b, through contact 20 of relay T, wire 22, contact 28 of relay L, latch contact 29, contact 30 of lever V, wire 38, and the winding of lock magnet NM to terminal o. With magnet NM energized, dog 3 controlled by this magnet will be raised to prevent engagement of dog 3 with the upper projection of the associated segment 4.

Lever V can, therefore, be moved to its D position where its further movement will be arrested by engagement of dog 3 of magnet RM with the upper projection of the associated segment 4. With lever V in its D position, reverse switch control magnet r will be energized by its circuit passing through terminal b, through contact 13 of release E, contact 14 of relay L, wire 15, contact 17 of lever V, and the winding of magnet r to terminal o. Lock magnet m also

will now be energized by its circuit passing from terminal b, through contact 43 of lever V, contact 44 of relay K, wire 45, and winding of magnet m to terminal o. With magnets m and r energized, mechanism M will operate switch F to its reverse position.

In the beginning of the operation of switch F, pole-changer P will open and hence relay K will be deenergized, thereby completing a second circuit for magnet m passing from terminal b, through contact 41 of relay K, wire 45, and the winding of magnet m to terminal o.

Upon completion of the operation of switch F to its reverse position, operation of pole-changer P will be completed to the corresponding position, causing a circuit to be completed for energizing relay K in the reverse direction. This circuit is exactly the same as the circuit previously traced for relay K except that current now flows from terminal b, through contact 27 of pole-changer P and from contact 23 of pole-changer P direct to terminal o. With relay K now energized by current of reverse polarity, its contacts 36 and 44 will be moved to their right-hand position. The circuit first traced for magnet m will therefore be open at contact 44, and the second circuit for magnet m will be open at contact 41 of relay K.

A circuit will now be completed for energizing magnet RM, passing from terminal b, through contact 27 of pole-changer P, contact 33 of lever V, wire 34, contact 35 of relay K, contact 36 of relay K in its right-hand position, contact 39 of lever V, wire 40, and the winding of magnet RM to terminal o. Magnet RM, upon becoming energized, raises its dog 3 which thereupon disengages the upper projection of the associated segment 4, permitting the leverman to complete the movement of lever V to its position R.

The procedure, and the operation of the apparatus for returning switch F to its normal position under normal conditions by moving lever V from its position R to its position B are similar to those just described for an operation of the switch to its reverse position, and will, therefore, be readily understood by reference to the drawing without further detailed description.

I will next assume that all parts of the apparatus have been returned to their normal condition and that track relay T then becomes deenergized either on account of the presence of a train or for some other reason. In an attempt to operate switch F while track relay T is deenergized, the leverman will turn release E to the mid-position, thereby opening contacts 13 and 25 and closing contact 21. With contact 21 closed, a circuit will be completed for energizing relay L which is the same as the circuit previously traced for this relay except that it includes contact 21 of release E instead of contact 20 of relay T.

If the leverman now closes latch contact 29, a second circuit will be completed for magnet NM which is the same as the circuit first traced for this magnet except that it includes contact 21 of release E instead of contact 20 of relay T. The leverman can, therefore, now place lever V in its D position.

The leverman will next continue the movement of release E to its reverse position, thereby opening contact 21 and closing contact 12. With contact 12 closed, a second circuit will be completed for energizing magnet r of mechanism M, passing from terminal b, through contact 5—6

of quick switch QS, contact 9 of lever V, wire 11, contact 12 of release E, wire 15, contact 17 of lever V, and the winding of magnet r to terminal o. On account of contact 25 being open, 5 relay K will be deenergized, and hence magnet m will be energized by its second circuit previously traced through contact 41 of relay K.

With magnets m and r energized, mechanism M will operate switch F to its reverse position, 10 causing pole-changer P to be also reversed. The leverman will now return release E to its normal position, thereby again closing contact 25 and completing the reverse energizing circuit previously described for relay K. Magnet RM will 15 thereupon be energized by the circuit previously traced, and hence the leverman can complete the movement of lever V to its position R.

If, for some reason, when the leverman energizes magnets m and r by operation of release E 20 as just described, switch F fails to move completely to its reverse position, and if the leverman then tries to return switch F to its normal position, or if he attempts to return lever V to its position N, he will be unable to do so because 25 contact 7-8 of quick switch QS will be open and he therefore cannot energize magnet n although contact 10 of lever V and contact 12 of release E have been closed.

It follows therefore that before the emergency release E can be used again for causing an operation of switch F, the switch must first complete its operation in response to the previously attempted control by release E. It will be apparent, therefore, that with the form of apparatus shown in Fig. 1 there can be no succeeding operation of the switch while track relay T remains deenergized until the switch has completed an operation in response to a previous attempt to cause an operation of the switch by release E. Between each operation of switch F controlled 40 by release E and a succeeding operation of switch F controlled by release E there must elapse an interval of time necessary for returning release E to its mid-position for closing contact 21, and for again moving release E from its mid-position 45 to its reverse position for closing contact 12.

Referring to Fig. 2, the apparatus shown therein may be used to replace that portion of the apparatus of Fig. 1 which is within the rectangle designated by the reference character J. The polarized relay G is the electrical equivalent of the quick switch QS. The relay G comprises two windings having a common terminal o, one winding being energized over the Nx contact 49 of lever V, and the other winding being energized over the Ry contact 50 of the lever. Polar contact 46 becomes swung to the right or the left according as one or the other winding of relay G is energized, that is, according as contact 49 or contact 50 of lever V is closed, and remains in the last operated position until relay G is subsequently pole-changed. Contacts 46-47 and 46-48 of relay G perform the same functions as contacts 5-6 and 7-8 of quick switch QS in Fig. 1. The cooperation of relay G of Fig. 2 with the apparatus of Fig. 1, for limiting the switch operation to one attempt for each operation of the emergency release, will be clear from the previous description.

Although I have herein shown and described only two forms of railway switch controlling apparatus embodying my invention, it is understood that various changes and modifications may be 75 made therein within the scope of the appended

claims without departing from the spirit and scope of my invention.

Having thus described my invention, what I claim is:

1. In combination with a railway switch having a normal and a reverse position, a manually operable lever movable between a normal and a reverse position, a first contact controlled by said lever which becomes closed when the lever is moved to its normal position and remains closed thereafter until the lever is moved to its reverse position, a second contact controlled by said lever which becomes closed when the lever is moved to its reverse position and remains closed thereafter until the lever is moved to its normal position, means including said first contact effective when said lever is moved from its normal near to its reverse position for moving said switch to the reverse position, means including said second contact effective when said lever is moved from its reverse near to its normal position for moving said switch to the normal position, locking means effective when a train is approaching said switch for preventing movement of the lever from its normal or its reverse position, and a manually operable time releasing device for rendering said locking means ineffective after the expiration of a time interval following actuation of said device.

2. In combination with a railway switch having a normal and a reverse position, a manually operable lever movable between a normal and a reverse position, a first contact controlled by said lever which becomes closed when the lever is moved to its normal position and remains closed thereafter until the lever is moved to its reverse position, a second contact controlled by said lever which becomes closed when the lever is moved to its reverse position and remains closed thereafter until the lever is moved to its normal position, a manually operable time releasing device which requires a time interval following actuation to complete its operation, means including said first contact effective after said device has completed its operation and said lever is moved from its normal near to its reverse position for moving the switch to its reverse position, means including said second contact effective after said device has completed its operation and said lever is moved from its reverse near to its normal position for moving the switch to its normal position, and means controlled by said switch for preventing movement of said lever to its normal or reverse position unless the switch has reached its normal or reverse position respectively.

3. In combination with a railway switch having a normal and a reverse position, a manually operable lever movable between a normal and a reverse position, a first contact controlled by said lever which becomes closed when the lever is moved to its normal position and remains closed thereafter until the lever is moved to its reverse position, a second contact controlled by said lever which becomes closed when the lever is moved to its reverse position and remains closed thereafter until the lever is moved to its normal position, a manually operable time releasing device having a middle contact which becomes closed for a brief interval following actuation of said device and also a front contact which becomes closed after the expiration of a time interval following said actuation and subsequent to the opening of said middle contact, means controlled by said middle contact for at times preventing movement of said lever from its normal or its reverse position unless said middle contact is closed, means includ-

ing said front contact and said first contact effective when said lever is moved toward the reverse position for moving the switch to the reverse position, means including said front contact and said second contact effective when said lever is moved toward the normal position for moving the switch to the normal position, and means controlled by said switch for preventing movement of said lever to the normal or the reverse position unless the switch has completed its normal or reverse movement respectively.

4. In combination with a railway switch having a normal and a reverse position, a manually operable lever movable between a normal and a reverse position, a first contact controlled by said lever which becomes closed when the lever is moved to its normal position and remains closed thereafter until the lever is moved to its reverse position, a second contact controlled by said lever which becomes closed when the lever is moved to its reverse position and remains closed thereafter until the lever is moved to its normal position, a manually operable time releasing device capable of assuming a first or a second position and requiring a time interval following actuation to reach said second position from said first position as well as to reach said first position from said second position upon subsequent actuation, means controlled by said device for at times preventing movement of the lever from its normal or its reverse position unless said device occupies said first position, means controlled by said first contact effective when said device occupies said second position and said lever is moved from its normal near to its reverse position for moving said switch to the reverse position, means controlled by said second contact effective when said device occupies said second position and said lever is moved from its reverse near to its normal position for moving said switch to the normal position, and means controlled by said switch for preventing movement of said lever to the normal or the reverse position unless the switch has reached its normal or reverse position respectively.

5. In combination with a railway switch having a normal and a reverse position, a manually operable lever having N, B, D and R positions, a first contact which becomes closed when the lever is moved toward the N position but beyond the B position and which remains closed thereafter until the lever is moved beyond the D position, a second contact which becomes closed when the lever is moved toward the R position but beyond the D position and which remains closed thereafter until the lever is moved beyond the B position; a manually operable time releasing device having a middle contact which becomes closed for a brief interval following actuation of said device and a front contact which becomes closed upon the expiration of a time interval following the opening of said middle contact, said middle contact becoming reclosed upon the expiration of a time interval following the opening of said front contact upon subsequent actuation of said device; means governed by said middle contact for at times preventing movement of said lever from the N or the R position if said middle contact is open, means controlled by said front contact and said first contact effective when said lever is moved to the D position for moving said switch to the reverse position, means controlled by said front contact and said second contact effective when said lever is moved to the B position for moving said switch to the normal position, and

means controlled by said switch for preventing movement of said lever beyond the B or the D position unless the switch has reached its normal or reverse position respectively.

6. In combination with a railway switch having a normal and a reverse position, a manually operable lever movable between a normal and a reverse position, a time releasing device having a middle contact which becomes closed for a brief interval upon actuation of said device and a front contact which becomes closed at the expiration of a time interval following the opening of said middle contact; a first contact which becomes closed when the lever is moved from its reverse near to its normal position provided said middle contact is closed, said first contact remaining closed thereafter until the lever is moved near to its reverse position; a second contact which becomes closed when the lever is moved from its normal near to its reverse position provided said middle contact is closed, said second contact remaining closed thereafter until the lever is moved near to its normal position, means controlled by said lever and including said first contact as well as said front contact for moving said switch to the reverse position, and means controlled by said lever and including said second contact as well as said front contact for moving said switch to the normal position.

7. In combination with a railway switch having a normal and a reverse position, a manually operable lever having N, B, D and R positions, a first contact controlled by said lever which becomes closed when the lever is moved to its N position and remains closed thereafter until the lever is moved to its R position, a second contact controlled by said lever which becomes closed when the lever is moved to its R position and remains closed thereafter until the lever is moved to its N position, means including said first contact effective when said lever is moved from its N to its D position for moving said switch to the reverse position, means including said second contact effective when said lever is moved from its R to its B position for moving said switch to the normal position, locking means effective when a train is approaching said switch for preventing movement of the lever from its N or its R position, and a manually operable time releasing device for rendering said locking means ineffective after the expiration of a time interval following actuation of said device.

8. In combination with a railway switch having a normal and a reverse position, a manually operable lever having N, B, D and R positions, a first contact controlled by said lever which becomes closed when the lever is moved to its N position and remains closed thereafter until the lever is moved to its R position, a second contact controlled by said lever which becomes closed when the lever is moved to its R position and remains closed thereafter until the lever is moved to its N position, a manually operable time releasing device which requires a time interval following actuation to complete its operation, means including said first contact effective after said device has completed its operation and said lever is moved from its N to its D position for moving the switch to its reverse position, means including said second contact effective after said device has completed its operation and said lever is moved from its R to its B position for moving the switch to its normal position, and means controlled by said switch for preventing movement of said lever to its N or its R position.

unless the switch has reached its normal or reverse position respectively.

9. In combination, a railway track switch, a manually operable lever having a normal position N and a normal indication position B as well as a reverse indication position D and a reverse position R arranged in the order named with relation to movement of the lever from the normal to the reverse position and arranged in the reverse order with relation to movement of the lever from the reverse to the normal position, a contact 10 of said lever closed only when said lever is in its position B, a contact 9 of said lever closed only when said lever is in its position D, a quick switch contact 5—6 of said lever which becomes closed when said lever is moved from its position B toward its position N and which then remains closed until said lever is moved from its position D toward its position R, a quick switch contact 7—8 of said lever which becomes closed when said lever is moved from its position D toward its position R and which then remains closed until said lever is moved from its position B toward its position N, means controlled by said switch for preventing movement of said lever from its position B toward its position N or from its position D toward its position R unless said switch occupies its normal or its reverse position respectively, a circuit including said contacts 5—6 and 9 in series for causing operation of said switch to its reverse position, and a circuit including said contacts 7—8 and 10 in series for causing operation of said switch to its normal position.
10. In combination, a railway track switch, a manually operable lever, a traffic contact which is closed when there is no traffic adjacent said switch but which becomes opened in response to a train adjacent said switch, means controlled by said lever and by said traffic contact when said traffic contact is closed for operating said switch to its normal and reverse positions, a manually controllable emergency release, and means controlled by said lever and by said emergency release for causing said switch to be successively operated to its normal and reverse positions while said traffic contact is open if and only if said switch completes an operation in response to each such attempt to cause an operation of said switch.
11. In combination, a railway track switch, a manually operable lever having a normal position and a normal indication position as well as a reverse indication position and a reverse position arranged in the order named with relation to movement of the lever from the normal to the reverse position and arranged in the reverse order with relation to movement of the lever from the reverse to the normal position, a contact of said lever which becomes closed when said lever is moved from its normal indication position toward its normal position and which then remains closed until said lever is moved from its reverse indication position toward its reverse position, a second contact of said lever which becomes closed when said lever is moved from its reverse indication position toward its reverse position and which then remains closed until said lever is moved from its normal indication position toward its normal position, a third contact of said lever closed only when said lever is in its normal indication position, a fourth contact of said lever closed only when said lever is in its reverse indication position, a circuit controlled by said first and fourth contacts for causing said

switch to be operated to its reverse position, and a second circuit controlled by said second and third contacts for causing said switch to be operated to its normal position.

12. In combination, a railway track switch, a manually operable lever, a traffic contact which is closed when there is no traffic adjacent said switch but which becomes opened in response to a train adjacent said switch, means controlled by said lever and by said traffic contact when said traffic contact is closed for operating said switch to its normal and reverse positions, a manually controllable emergency release having a normally closed contact and having a normally open contact which becomes closed upon the lapse of a period of time after said normally closed contact opens, a switch indication relay controlled by said normally closed contact as well as by said switch, and means controlled by said normally open contact and by a back contact of said switch indication relay for causing operations of said switch when said traffic contact is open.

13. In combination, a railway track switch, a manually operable lever, a traffic contact which is closed when there is no traffic adjacent said switch but which becomes opened in response to a train adjacent said switch, means controlled by said lever and by said traffic contact when said traffic contact is closed for operating said switch to its normal and reverse positions, a manually controllable emergency release, means controlled by said lever and by said emergency release for setting said switch into operation toward its normal or its reverse position while said traffic contact is open, and means controlled by said switch for preventing further control of said switch by said lever and said emergency release until said switch has reached said normal or reverse position respectively.

14. In combination, a railway track switch, a manually operable lever having a normal and a reverse position as well as a normal indication position adjacent said normal position and a reverse indication position adjacent said reverse position, a polarized relay, a normal polar contact of said relay closed when said relay is energized by current of normal polarity and which then remains closed until said relay is energized by current of reverse polarity, a reverse polar contact of said relay closed when said relay is energized by current of reverse polarity and which then remains closed until said relay is energized by current of normal polarity, normal and reverse energizing circuits for said polarized relay closed by said lever in its normal and reverse positions respectively, means controlled by said normal polar contact and by said lever in its reverse indication position for causing said switch to be moved to its reverse position, and means controlled by said reverse polar contact and by said lever in its normal indication position for causing said switch to be moved to its normal position.

15. In combination, a railway track switch, a manually operable lever having a normal and a reverse position as well as a normal indication position adjacent said normal position and a reverse indication position adjacent said reverse position, a polarized relay, a normal polar contact of said relay closed when said relay is energized by current of normal polarity and which then remains closed until said relay is energized by current of reverse polarity, a reverse polar contact of said relay closed when said relay is energized by current of reverse polarity and which then remains closed until said relay is energized by current of reverse polarity and which then re-

- mains closed until said relay is energized by current of normal polarity, normal and reverse energizing circuits for said polarized relay closed by said lever in its normal and reverse positions respectively, means controlled by said normal polar contact and by said lever in its reverse indication position for causing said switch to be moved to its reverse position, means controlled by said reverse polar contact and by said lever in its normal indication position for causing said switch to be moved to its normal position, and means controlled by said switch for preventing movement of said lever from each of said indication positions to the adjacent normal or reverse position until said switch has reached the corresponding normal or reverse position respectively.
16. In combination, a railway track switch, a manually operable lever having a normal and a reverse position and also having a normal and a reverse indication position, the electrical

equivalent of the well-known quick switch which is commonly associated with such a lever comprising a polarized relay having a normal and a reverse polar contact each of which becomes closed when its relay becomes energized by current of a corresponding polarity and then remains closed until its relay becomes energized by current of the opposite polarity, normal and reverse circuits closed by said lever in its normal and reverse positions for energizing said relay by current of normal or reverse polarity respectively, means controlled by said normal polar contact and by said lever in its reverse indication position for causing said switch to be moved to its reverse position, and means controlled by said reverse polar contact and by said lever in its normal indication position for causing said switch to be moved to its normal position.

MELVIN A. PENROD. 20
